UNITED STATES PATENT OFFICE.

HENRY A. BOWERS, OF INDIANA, PENNSYLVANIA.

LAUNDRY STAND.

Application filed January 19, 1920. Serial No. 352,308.

To all whom it may concern:

Be it known that I, HENRY A. BOWERS, a citizen of the United States, residing at Indiana, in the county of Indiana, and State of 5 Pennsylvania, have invented new and useful Improvements in Laundry Stands, of which the following is a specification.

The present invention has reference to a laundry stand.

10 The object of the invention is to produce in a single article of furniture, means for supporting removable ironing boards of different sizes, tubs for washing and wringing, a wringer, and a clothes hamper or basket.

15 A further object of the invention is to produce a device of this character comprising a bench-like body having a slidable extension longitudinally movable through one 20 of the ends thereof and suitably supported when drawn outwardly so as to sustain tubs or clothes hampers, the body at the end thereof provided with the slidable extension having an upstanding portion provided with 25 means whereby removable ironing boards may be supported, and the said body having also removably associated therewith brace means for more effectively supporting said boards, the upstanding member being also 30 provided with means for supporting a wringer.

Other objects and advantages of the improvement will appear as the nature thereof is more fully disclosed, reference being had 35 to the accompanying drawings, in which:

Figure 1 is a front elevation of the improvement.

Figure 2 is a longitudinal sectional view approximately on the line 2—2 of Figure 1, 40 showing an ironing board supported upon the improvement.

Figure 3 is a transverse sectional view approximately on the line 3—3 of Figure 2.

Figure 4 is a detail view illustrating the 45 manner in which the pivoted stop member for the slidable extension is normally sustained in position for preventing the entire withdrawal of the slidable extension.

Figure 5 is a side elevation of the slidable 50 extension.

My improvement includes a bench which is broadly indicated by the numeral 10. The bench has its front legs 11 of a less length than its rear legs 12. The top of the bench, 55 indicated by the numeral 13 has an upstanding ledge 14 slightly inward of one of its

edges, being flush with the inner face of one of the rear legs 12 and terminating approximately at the inner edge of one of the front legs 11. This ledge is provided with a notch 15 arranged diametrically opposite a similar notch 16 in the opposite edge of the top 13. The side members 17 arranged between the confronting edges of the front and rear pairs of legs have socket or staple members 18 60 alining with the notches 15 and 16. If desired, and as illustrated by the drawings, the ledge 14 may be provided by the upper portion of one of the side members 17. The legs 11 have their outer edges connected by a front plate 19 and the front legs are also 65 suitably braced by a round or rung member 20 and a cleat 21 at the upper portion of the plate 19 that supports the forward end of the top 13.

The portions of the rear legs 12 which extend above the top 13 have their upper and outer corners notched to receive a transverse brace 21, and below the brace 21 said leg extensions are connected by a plate 23. Below 80 the plate there is a transverse cleat 24, and in a line with the lower edge of the cleat, connected thereto as well as to the sides, top and front cleat of the bench are longitudinally extending strips 25. Below the strips 25 are 85 similar strips 26 which are also secured to the rear legs, sides, front legs, as well as to the front plate 19. The space between the cleats provide ways for a slidable extension 90 27, the slidable extension, of course, resting upon the lower strips 26. The slidable extension may be of any desired depth, but is preferably comparatively shallow, and the said slidable extension, at the outer end thereof is provided with downwardly extending legs 28, the said legs being connected by a round 29 and at a suitable distance above the round with transverse plates or 95 cleats 30. The plates 30 are of a greater length than the width of the slidable extension so that the same abut with the lower portion of the rear legs 12 when the slidable extension is closed. The legs 28 for the slidable extension may be provided with rollers 100 whereby the same may freely travel over the floor surface when the slidable extension is open.

Between the legs and the bottom of the slid- 110 able extension are angle plates 31, while piv- 110 110 otally secured, as at 32 to the lower support- 110 ing strip 26 for the slidable extension is a stop plate 33. The plate 33 has its outer

end cut at an angle as indicated by the numeral 34, and being in the path of contact with the inner edge of one of the angle plates 31, this end 34 of the stop is arranged 5 parallel with the inner transverse cleat at the end of the slidable extension so that the contacting engagement between these elements will prevent the entire withdrawal of the slidable extension from the bench. It will 10 be apparent, however, that the stop plate may be swung downwardly out of the path of engagement with the cleat, which for distinction is indicated by the numeral 35, so that the slidable extension may be wholly 15 withdrawn from the bench. When the slidable extension is closed in the bench the cleat 35 is engaged by a pivoted latch plate 36 which is also pivoted to one of the supporting strips 26 for the slidable extension 27. 20 The slidable extension is designed to serve as a support for a clothes hamper, wash tub or the like.

The upper portion of the rear legs, including the cleat and plate connected to the 25 same above the top of the bench provide a support for ironing boards, and a wringer, and for the sake of distinction the said extensions will hereinafter be referred to as an upright support. Between the sides of the 30 upright support, adjacent to the top thereof there are two spaced horizontally disposed rounds 37 and 38 respectively. The rounds 37 and 38 are designed to receive therebetween a curved lip member 42 formed upon 35 the inner and widened end of an ironing board 43. The lip underlies the inner round 38 so that the rear portion of the board 43 will rest upon the outer round 37. In this connection it should be stated that any de- 40 sired number of ironing boards may be em- ployed with the improvement, all of the same, however, being provided with a lip and with a transverse cleat 44 upon the under face thereof which is located a con- 45 siderable distance outward of the lip end of the board. Each of the cleats is channeled for the major portion of its length, the said channel terminating adjacent to the ends of the cleat and forming a socket 45 for 50 the upper element 46 of a substantially U-shaped brace member 47. The parallel legs of the brace member 47 are formed with lateral extensions or offset portions 48 which rest directly upon the top of the bench 10,

and at the ends of the said angle portions or shoulders 48 there are depending portions 49 providing what may be termed fingers, and these fingers are adapted to pass through the notches 15 and 16 and to be received in the sockets or staples 18 on the 55 sides of the bench. In this manner the ironing boards are supported at both their rear ends and at their centers. When clothes baskets or wash tubs are arranged upon the bench 10 the same will be held against lateral 60 movement from off the bench by the ledge 14, the side of the bench opposite that provided with the ledge being what may be termed the front side adjacent which the operator stands. The tubs employed may 65 be of a particular construction having drain 70 openings at the bottom thereof.

The bench also serves as a supporting means for wash tubs and clothes baskets. When the wringer is employed, the same is 75 attached to the rear extension or support of the bench in the usual manner, a tub containing the clothes is placed on the slidable extension which is brought to its extended 80 position and the basket to receive the clothes is placed on the slidable extension in a position to receive the clothes from the wringer.

Having thus described the invention, what is claimed as new, is:—

A device of the class described comprising a bench provided with legs at the corners thereof, spaced strips secured to the front and rear legs upon opposite sides of said bench, a plate secured to the front legs 90 of said bench, a slidable extension disposed between said strips, legs extending downwardly from one end of said extension, a transverse plate secured to the legs of said extension adjacent to the upper end thereof, 95 extending beyond their outer edges and adapted to engage the rear legs of said bench, a transverse cleat disposed at the opposite end of said slidable extension and adapted to engage said plate, triangular plates disposed between the legs and the bottom of the slidable extension, a stop plate pivotally secured to one of said strips and adapted to engage said cleat and a latch plate pivotally secured to one of said strips and adapted to 100 engage said cleat.

In testimony whereof I affix my signature.

HENRY A. BOWERS.
